UNITED STATES PATENT OFFICE.

THOMAS O'HERN, OF KEW GARDENS, NEW YORK, ASSIGNOR TO ARTHUR T. O'HERN, OF KEW GARDENS, NEW YORK.

NITROGLYCERIN DYNAMITE.

No Drawing.

Application filed April 2, 1926. Serial No. 99,404.

This invention relates to fumeless explosives of the nitroglycerin dynamite type.

Heretofore with the use of dynamites of the nitroglycerin type it has been necessary 5 to permit a considerable time to elapse before workmen could return to the facing after a shot had been fired, even with a powerful ventilating system, since the material loosened by the shot held the gases and fumes, 10 and the workmen by pick and shovel in removing the loose material would release these fumes directly in their faces. Various disabilities and diseases have thus been incurred, some of which have been permanent in character. It has therefore been sought to obtain a nitroglycerin dynamite which was 15 fumeless and without deleterious effect upon the health but, so far as the inventor is aware, without success. It has therefore been customary to employ gun gelatins or gelatin 20 dynamites which are gun cottons saturated with nitroglycerin in various proportions and which are expensive and require special handling.

25 One of the objects of this invention is therefore to present a nitroglycerin dynamite which gives off no poisonous gases or fumes upon detonation, and therefore is excellently adapted for subterranean work, since the 30 workmen are permitted to immediately return without a preliminary ventilation. It has been employed successfully in underground work in tunneling, mining, etc., and is especially valuable where the ventilation is 35 poor.

According to this invention, a nitroglycerin 40 dynamite is prepared with a combined organic and inorganic absorbent material, and with an inorganic oxygen-bearing substance to produce fumeless, odorless, and non-dam- 45 gerous resultant products. The requirements of oxygen and the supply of oxygen available are carefully balanced in the explosive for this purpose, and the further ingre-

dients added assure this effect when the mixture is detonated.

In order to produce 300 lbs. of a product of 60% equivalent strength, the following proportions of ingredients may be employed:

	Lbs. 50
Nitrate of soda.	64
Infusorial earth.	30
Wood flour.	20
Potassium nitrate.	3
Magnesium carbonate, ground.	3 55
Nitroglycerin	180
	300

In making the mixture, the nitrate of soda and infusorial earth are thoroughly mixed in a waterproof vessel and then the other dry ingredients are added and the whole mixed again. The nitroglycerin is then added and the mass again mixed very thoroughly.

The oxygen balance of this compound is so perfect that all poisonous gases and fumes burn each other up, so to speak, and no disagreeable odor is left.

While the above composition is the preferred form and has given good results, it will be understood that other inorganic oxygen-bearing substances may be employed in proper proportion, such as manganese dioxide and potassium chlorate.

I claim:

1. A sixty percent nitroglycerin dynamite containing sixty-four parts by weight of sodium nitrate, thirty parts by weight of infusorial earth, twenty parts by weight of comminuted wood product, three parts by weight of potassium nitrate, three parts by weight of ground magnesium carbonate, and one hundred eighty parts by weight of nitroglycerin.

2. A high explosive nitro-glycerin dynamite free from nitrocellulose, containing organic and inorganic absorbent material and

an inorganic oxygen-bearing and releasing agent, said organic absorbent material being a comminuted wood product, the free oxygen of said agent liberated at detonation being at least in a chemically equivalent proportion to oxidize the gases given off by said nitro-glycerin and said organic absorbent ma-

terial, and being approximately nine parts by weight of nitro-glycerin to three parts by weight of oxygen-bearing agent to one part by weight of organic absorbent material.

In testimony whereof, I affix my signature.

THOS. O'HERN.
